3,089,726 GRAPPLE

Robert G. LeTourneau, P.O. Box 2307, Longview, Tex.
Filed Jan. 18, 1961, Ser. No. 33,434
1 Claim. (Cl. 294—88)

My invention relates to grapple devices, and more particularly to grapple devices of the general type wherein opposing pivoted fingers engage a load and are urged toward the closing position by gravity and load weight, and are powered toward the open position.

The grapple of my invention is especially applicable to logging operations, though by no means confined thereto. While there have been numerous grapples devised in the prior art of which I am aware, none have proven to be entirely satisfactory.

It is accordingly the general object of my invention to provide an improved grapple.

Another object of my invention is to provide a grapple which shall be capable of attaining a full open position as well as a full closed position.

Another object of my invention is to provide an improved grapple wherein the suspension cable is the only cable required.

Another object of my invention is to provide an improved grapple wherein the grapple may be positively powered to open position.

Another object of my invention is to provide an improved grapple wherein means for positively powering the grapple to open position is mounted on the grapple itself.

Another object of my invention is to provide a grapple with an improved control arrangement.

Another object of my invention is to provide an improved grapple structure.

These and other objects are effected by my invention as will be apparent from the following description taken in accordance with the accompanying drawings, forming a part of this application, in which:

FIG. 1 is a schematic perspective view of a grapple in accordance with a preferred embodiment of my invention;

FIG. 2 is a side elevational view, partly in phantom, showing the opposite side of the grapple of FIG. 1;

FIG. 3 is a schematic side elevational view showing the grapple of FIG. 1 in maximum closed position;

FIG. 4 is an end elevational view of the grapple of FIG. 1; and

FIG. 5 is a schematic block diagram showing an electric circuit control arrangement.

Referring now to the drawings, the grapple, in accordance with a preferred embodiment of the invention, includes a single or middle load handling finger 11, and a pair of double or outer load handling fingers 13, 15. The double load handling fingers 13, 15 are maintained in rigid parallel spaced relation by a spacer member 17 and a main pivot structure 19. The spacer member 17 extends between the double fingers 13, 15 at their approximate centers and is fixed, as by welding, to their inner side surfaces. The load contacting surface 21 of each finger 11, 13, 15 is concave and is approximately a little more than a quarter of a nearly circular ellipse. The fingers are all pivoted adjacent the upper end position of their load contacting surfaces on a main pivot, comprising a pin 23, and suitable retainer means. A pair of sleeves 25 on the pin 23, one between each outer finger and the middle finger, act as spacers.

The middle finger 11 has an integral portion which extends laterally beyond the main pivot 19 and which may be termed a closer arm 21. The middle finger 11 also has an integral portion which extends generally upwardly in the general direction of a tangent to the finger

2

outer profile surface at its approximate center, and which integral extension portion may be termed an opener arm 29.

The grapple also includes a bridge structure 31 and a pivot link 33. The bridge structure has a generally horizontal portion made up of a pair of spaced parallel members 35, and a downwardly and outwardly depending member 37 which is integrally fixed to the parallel members at its upper end and pivoted to the middle tooth 11 adjacent the juncture of the middle tooth and the opener arm at 39. A pivot link member 33 having the general shape of an isosceles triangle is pivoted at each of its base side apices at 41, 43 to a respective one of the double fingers 13, 15 at its rear side center region. The pivot link member 33 is pivoted at its apex region at 45 to the bridge structure 31 adjacent the outer end of the bridge structure.

The grapple is suspended by a single load cable 47, as from a boom (not shown). The load cable 47 bears on a first sheave 49 which is carried by the horizontal portion of the bridge structure 31 at its approximate center, and passes downwardly and around a second sheave 51 which is carried by the closer arm 27 adjacent its outer end. The load cable 47 then passes upwardly and is dead ended on the horizontal portion of the bridge structure at 53.

The middle finger opener arm 29 is controlled by a cable 55 which is reeled off a drum 57 and fixed at the free end 59 to a projection 61 of the opener arm 29. The cable drum 57 is driven by a reversible electric motor 63 through a gear box 65. The motor 63, drum 57, and gear box assembly 65 are fixedly mounted on the bridge structure 31. Electric power is supplied to the electric motor via a spring biased reel (not shown), which may be fixed to the boom or other structure (not shown) from which the grapple is suspended. This reel carries an electric conductor cable 67 which supplies power to the reversible motor 63. The motor 63 is provided with an electromagnetic friction brake 64 of a type such that when the motor is energized, the brake 64 is released, and when the motor is de-energized, the brake 64 is set. Eye rings 69 are provided on the grapple, to which tag lines (not shown) may be secured if desired.

In FIG. 5 there is shown in schematic block form a power source 71, which supplies power respectively through a hoist controller 73 to a hoist motor 75 to control movement of cable 47, and through a grapple motor controller 77 to control the grapple motor 63, and hence, movement of cable 55.

In operation, when it is desired to pick up a load, for example a log, the grapple motor 63 is run in the direction to reeve cable 55 onto the drum 57, thus pulling the opener arm 29 toward the motor 63, forcing the middle grapple finger 11 to move away from the double fingers 13, 15, thus opening the grapple. Then hoist cable 47 is reeved out, lowering the grapple down onto the log. The grapple may be oriented relative to the log by means of tag lines (not shown). Since the weight of the grapple bearing on cable 47 tends to move the closer arm 27 upwardly to try to close the grapple, while the tension of cable 55 on opener arm 29 tries to open the grapple, then the grapple will be held in any degree of open or close by means of the brake 64 when the motor 63 is de-energized. When the grapple has descended into pick-up position on the load, the motor 63 is energized in the reverse direction to reeve out cable 55, while tension of the hoist cable 47 is utilized to close the grapple fingers 11, 13, 15 onto the load. As the load is picked up, the additional weight on the hoist cable 47 causes the fingers to grip the load harder. Thus, there is no possibility that the load will be released until the motor 63 is energized in the proper direction to open the fingers 11, 13, 15.

Although I have shown my invention in only one form, it will be apparent to those skilled in the art that it is not so limited, but is susceptible of various changes and modifications without departing from the spirit thereof.

I claim:

A grapple comprising opposed load engaging fingers having a common pivot, a grapple closer arm integral with one of said fingers and extending laterally of said pivot in the direction away from said finger, a first sheave mounted on said closer arm, a grapple opener arm integral with said one finger and extending outwardly therefrom, a bridge structure, a link member, means pivoting said bridge structure at one end to said one finger at the outer center portion thereof, means pivoting one end of said link member to the other end portion of said bridge structure, means pivoting the other end of said link member to said other

5 finger at the outer center portion thereof, a second sheave mounted on said bridge structure above said common pivot, a hoist cable bearing on said second sheave, passing downward and around said first sheave and thence upwardly and dead-ended on said bridge structure, an electric motor mounted on said bridge structure, a cable drum driven by said motor, cable on said drum and having one end dead-ended on said opener arm, and means for supplying power to said motor.
